LEO A. MEHLER, OF EAST CHICAGO, INDIANA, AND ELLSWORTH J. WESTCOTT, OF CHICAGO, ILLINOIS, ASSIGNEES TO FREYN ENGINEERING COMPANY, OF CHICAGO, ILLINOIS, A CORPORATION OF MAINE

WASTE GAS SUPERHEATER

Application filed October 9, 1930. Serial No. 487,475.

This invention relates to superheaters and is illustrated as used in connection with a waste heat boiler although it may be applied to other types of boilers and used generally 5 for heat exchanging apparatus. In the generation of steam by the use of waste heat boilers large quantities of waste gases of comparatively low temperatures are used. In attempting to apply superheaters to this 10 type of boiler a slightly different problem is presented because of the larger volume of gases and because the temperature difference between the waste gases and saturated steam is not as great as with other apparatus. This 15 low temperature difference added to the large volume of gases necessitates a greater amount of heating surface in the superheater and heretofore a correspondingly large amount of space.

One object of this invention is to provide 20 a superheater of greater efficiency and requiring less space than those heretofore known, especially when used with waste gas boilers.

Another object of the invention is to decrease 25 the draft loss by diminishing the length of flue necessary to house the superheater.

An additional object of the invention is to 30 provide a superheater in which the headers and units are away from the front of the boiler so that they may be out of the way when the boiler tubes are blown. As it is necessary to blow these tubes quite frequently, 35 the matter of convenience and ready access is very important.

A further object of the invention is to provide 40 a superheater unit in which the pressure drop of the steam is at a minimum, considering the amount of heating surface.

Other objects of the invention will appear 45 from the following description, drawings and claim.

In the drawings, in which like numerals 50 are used for similar parts throughout:

Figure 1 is a vertical sectional view of the apparatus taken along the line 1-1 of Figure 2;

Figure 2 is a side elevation of the superheater connected to the boiler; and

Figure 3 is a fragmentary longitudinal section showing the superheater units with the braces removed.

In the embodiment of the invention which has been illustrated by way of example, the 55 superheater is located at the front end of the boiler 10. The usual saturated steam connection 12 is used as well as the superheated steam outlet 14. Connected to the outlet 12 is the saturated steam distributing header 16 60 and communicating with the connection 14 is the superheated steam outlet header 18. According to one feature of this invention these headers are now located at the side of 65 the boiler as shown instead of at the front of the boiler in accordance with the prior practice. As it is necessary to blow out the boiler tubes frequently and as this operation is performed from the front of the boiler, it is found that the location of the headers at 70 the side is a great advantage. This not only leaves the front unobstructed but it takes away from the front the extreme and disagreeable heat which is necessarily found near these headers.

Each unit of the superheater includes the 75 two pipes 22 and 24. The pipes 22 and 24 lie in the same plane, the loop of one being between the two legs of the loop of the other. If desired one or both of the pipes may be 80 given a plurality of loops. In that case such double loop pipe is preferably arranged with first a wide bend such as 26 and then a narrow bend such as 28, thus avoiding having two sharp bends adjacent to each other.

As illustrated in Figures 2 and 3, the pipes 85 are quite close together, each being held in place by suitable braces 30. This close spacing is desirable in order to obtain a maximum of heating surface within a given space. In 90 order to accomplish this the two pipes 22 and 24 are mounted on header 16 and likewise header 18 at the same longitudinal position, that is, they are spaced circumferentially but not longitudinally.

A unit comprising two short pipes is much 95 more efficient than would be a single pipe twice as long. A long single pipe in a space of the same width would necessarily have twice as many bends. To keep from spread- 100

ing over a greater length of passage each bend would have to be of the sharp type numbered 28. Thus the single double length pipe would offer over twice as much resistance to steam flow, and as the cross-section would be only half that of two pipes, the pressure drop across the single pipe would be very much greater than across the two pipe unit of this invention.

10 Any number of units consisting of pairs of pipes 22 and 24 may be used as dictated by the amount of steam generated by the boiler. Then by knowing the temperature of the waste gases passing the superheater these units may be made of just the right length to obtain the required heating surface to furnish superheat to the saturated steam generated by the boiler.

Having thus described our invention, it is 20 to be understood that many other embodiments of the invention, including some in improved form, will be apparent and in the course of time will be devised by those skilled in the art. Our invention includes all of 25 these which come within the spirit of the following claim, construed as broadly as the prior art will permit.

We claim:

30 The combination of a waste gas boiler having tubes extending longitudinally therethrough, being adapted to have said tubes blown from the front end, and having an inlet flue at the front end; with a waste gas superheater in said flue comprising headers 35 located at the side of said boiler and pairs of horizontally extending pipes in front of said boiler, the two pipes of each pair being U-shaped and connected in a single radial plane to each header, said headers being sufficiently separated so that the U-shaped pipes 40 may be withdrawn between said headers while retained in their original planes.

Signed at East Chicago, Indiana, this 30th day of September 1930.

45 LEO A. MEHLER.
